United States Patent Office.

JACOB F. GIBSON, OF CHESTNUT LEVEL, PENNSYLVANIA.

Letters Patent No. 97,903, dated December 14, 1869.

IMPROVEMENT IN GRAIN-DRILLS.

The Schedule referred to in these Letters Patent and making part of the same.

To all whom it may concern:

Be it known that I, JACOB F. GIBSON, of Chestnut Level, in the county of Lancaster, and State of Pennsylvania, have invented a new and useful Improvement in Grain-Drills; and I do hereby declare that the following is a full, clear, and exact description of the construction and operation of the same, reference being had to the accompanying drawings, making a part of this specification, in which—

Figure 1 is a side elevation, and

Figure 2, a plan view.

This invention relates to a seed-tube, pivoted in its drag-bars, in such a manner that it may yield to an immovable obstruction.

The invention consists in bracing the seed-tube in the drag-bars, by means of a chain attached at its ends, to the tube, above and below the point of junction of the latter with the supporting arms, and passing over a toothed wheel, held between the supporting arms so tightly that it will sustain the tube in the proper position against the ordinary resistance of the soil, and not so tightly but that it will rotate sufficiently to allow the tube to clear an immovable obstacle.

In the drawings—

A is the seed-tube, and
B the drag-bars to the end of which the tube is pivoted.

C is the toothed wheel, placed on a shaft, c, between the arms B, which are capable of being tightened upon the wheel, by means of a nut, screwed upon the projecting end of the shaft c.

D is the chain, connected, at its ends, with the tube, and passing over the toothed wheel.

After the obstruction has been passed, it is only necessary to loosen the wheel C, turn it so as to draw the tube, by means of the chain, once more into the proper position, and then tighten the wheel again.

Having thus described my invention,
What I claim as new, and desire to secure by Letters Patent, is—

The clamping-bolt c, toothed wheel C, and chain D, arranged with reference to the seed-tube and drag-bar of a grain-drill, substantially as described and for the purpose set forth.

JACOB F. GIBSON.
